UNITED STATES PATENT OFFICE

2,159,105

OSCILLATOR FOR MULTIPLE WAVE BAND RECEIVERS

John D. Reid, Philadelphia, Pa., assignor to Radio Corporation of America, a corporation of Delaware

Application April 30, 1937; Serial No. 139,846

13-Claims. (Cl. 250—36)

The present invention relates to oscillators for multiple wave band receivers, and more particularly to a multiple wave band tunable oscillator of the Hartley type for multiple wave band spread tuning systems, wherein separate inductance coils are used in each of the tuning bands having grid, anode, and intermediate cathode circuit connections, and has for its object to provide a simplified switching system for the circuits and coils of an oscillator of that type.

It is also an object of this invention to provide a simplified switching system for an oscillator of the above type whereby it may be utilized effectively in a band spread system for tuning a multiple wave band receiving system as shown, described and claimed in my copending application Serial No. 139,847, filed April 30, 1937, for "Multiple wave band receivers", and assigned to the same assignee as this application.

Such a system may cover a plurality of narrow tuning ranges or bands which may be chosen as follows:

25	Band	Kc. range	Band width in kc.
Standard broadcast		550-1,550	1,000
49 meters		5,950-6,255	305
31 meters		9,405-9,700	295
25 meters		11,675-11,925	250
19 meters		15,070-15,380	310

whereby improved band spread of the tuning induction may be obtained, the 300 kc. tuning range in each of several bands being less in kilocycle width than the standard broadcast band for the same tuning indicator range.

In any system for wave band change, it is desirable to decrease the number of circuit changes to a minimum, and it is therefore an object of the present invention to provide an oscillator for multiple wave band receivers wherein the multiple wave band switching of the oscillator is not only simplified, but also the number of switching contacts to be changed is reduced to a minimum.

It is also an object of the present invention to provide an improved coil switching system for a multiple frequency band oscillator of the Hartley type, wherein a plurality of oscillator inductances are provided for a plurality of frequency bands and wherein switching of the cathode and anode connections may be eliminated or reduced to a minimum. In carrying this object into effect, in connection with a band spread or multiple wave band tuning system, the switch-

ing operation for the cathode and for the anode may be eliminated and the band changing may be reduced to a single switching connection for the grid.

Other objects and advantages of the invention will be seen from the following description when considered in connection with the accompanying drawings, and its scope will be pointed out in the appended claims.

In the drawings, Figure 1 is a schematic circuit diagram of a multiple frequency oscillator for a multiple wave band receiver, showing one embodiment of the invention, and

Figure 2 is a similar schematic circuit diagram of a modification of the circuit of Fig. 1, showing a further embodiment of the invention.

Referring to Fig. 1, an oscillator tube 5 having a cathode 6, an anode 7, a control grid 8, together with screen and suppressor grids 9 and 10 respectively, is selectively connectable with a series of tuning inductances 11 to 17 inclusive, through a control switch 18, preferably of the rotary type, the contacts of which are shown in the drawings as projected in a plane, for a better understanding of its operation. In a multiple wave band receiver, the switch is one unit of a gang wave band changing switch, as indicated. A variable tuning capacitor 19 is provided for tuning the various inductances referred to, and this is also one unit of a gang tuning capacitor in a multiple wave band receiver, as indicated.

The switching arrangement provided by the switch 18 is such that, through the usual grid capacitor 20, the control grid 8 is selectively connectable with the high potential or grid ends of the tuning inductances 11 to 17, inclusive, in a succession of steps provided by contacts indicated at 21. This connection is provided in the switch by a movable conductor or contact element 22 which engages a fixed contact 23 for the grid connection and is provided with a contact 24 for engaging successively with the contacts 21 for the various inductances.

The inductances 11 to 17, inclusive, may be considered to be tunable to provide oscillations for mixing with incoming signals in each band, to provide a desired intermediate frequency in the receiver. The mixer connection is made from the cathode by a connection lead as indicated at 25.

The coils 11 to 17, inclusive, are tunable by the variable tuning capacitor 19, which has two stator sections indicated at 26 and 27, providing two differing tuning capacity ranges. For

55

example, the section 26 may provide the usual variable tuning capacity range of substantially 480 m. m. f. and the section 27 provides a range of substantially 15 m. m. f. as the rotor 28 is moved through the same tuning range of movement.

The switch 18 provides additional contacts 30, 31 and 32 for changing connection with the tuning capacitor stators 26 and 27. Connections are shown whereby the main stator 26 provides tuning control through the A, B and C bands with the coils 11, 12 and 13, respectively, as the conductor 22 is moved progressively upward, as viewed in the drawings, in three successive steps by the operation of the switch. Manual control of the switch is indicated by the control knob 33.

For the A band, a series tuning capacitor is provided at 34, for the B band at 35, and for the C band at 36, whereby the tuning capacitor 19 is caused to "track" with other tuning functions in the receiver through the desired frequency ranges. The capacitor 35 is connected through a lead 37 with a contact 38, and the capacitor 36 is connected with the contact 32.

It will be noted that the contacts 23 and 31 are arranged to remain connected together through the conductor 22 for the B and C bands, and that the additional stator 27 is in circuit. This permits the B band coil 12 to be connected with the contact 31 in common with the stator 27 through a lead 39, so that an additional switching connection is eliminated.

All of the coils except the A band coil are connected to ground or chassis at the opposite terminal from the grid terminal, as indicated. For the A band, a separate grounded cathode coil 40 is provided, having a cathode connection provided by leads 42 and 43 through the switch 18 at contacts indicated at 44, 45 and 46. For the contacts 44 and 45 a conductor element 47 movable with the element 22 is provided, and the conductor has a contact 48 for engaging the contact 46 in the A band position as shown. The conductor 47 is joined through an insulating means 50 with a conducting element 51, which in turn is joined with the conductor 22 through a second insulating element 52, whereby the movable switch elements may be moved together to provide a predetermined contact relation in seven successive steps.

The cathode switching connections provided by the contacts 44, 45 and 46 permit the cathode to be connected with the cathode coil 40 for the A band, and then selectively with a trimmer capacitor 54, through a contact 55, for the B band connection. At the same time, the cathode connection is changed from the A band coil 40, through the conductor 51 and a contact 56, to provide the cathode tap connection 57 on the B band coil 12. This is maintained thereat for each of the succeeding higher frequency bands, as the conductor 51 engages and connects the contacts 56, 44 and 45 together.

Feed-back from the anode and the screen grid, to ground and the grounded ends of the inductances for the various tuning bands, is provided through a ground connection indicated at 60, and a by-pass capacitor 61 from the screen grid and anode. Operating potential is provided for the screen grid and anode through a coupling resistor 62 from any suitable source (not shown).

The variable tuning capacitor section 27 is utilized in tuning the short wave or band spread bands, and in order to obtain stability of the oscillator with respect to small changes of ca-

pacity as caused by vibration and movement of leads in the operation of the oscillator, a padding capacitor 63 is arranged to be connected in shunt across the 49-meter band tuning circuit by a contact element 64 on the movable conductor 22, and is maintained in connection across the circuit by additional contacts 65, 66 and 67, also connected with the movable conductor 22 as shown.

To keep the tuning range substantially the same throughout in a relatively narrow kilocycle band of substantially 300 kc. for the other higher frequency bands, additional padding capacitors 68 and 69 are connected with switch contacts 70 and 71 through the contacts 64, 65, 66 and 67, in the same manner as the contact 72 for the padding capacitor 63. By the switching means shown, the additional padding capacitors are shunted across the oscillator tuning circuit as the switch 18 is moved to adjust the tuning in the higher frequency ranges. In the present example, substantially 100 m. m. f. is added by each of the capacitors 63, 68 and 69, making a total of 300 m. m. f. shunted across the oscillator circuit for the 25 and 19 meter bands.

The padding capacitors 63, 68 and 69 are of a design having a slightly negative coefficient with regard to capacity with increase in temperature to compensate for the normal increase in inductance of the tuning coils with temperature, thus holding the frequency and dial calibration constant.

In a band spread tuning system for which the oscillator is particularly effective, a change of 10 kc. may result in a five degree movement on a dial scale having, for example, a scale covering substantially 180°, and because of excessive overlap at the ends of the bands this would reduce the effectiveness of the band spread.

By maintaining the cathode connection permanently at the cathode tap on a lower frequency band coil, such as the B band coil, which has a higher inductance than that of the other shorter wave coils, the latter may each be connected at the grid end, selectively in parallel with the coil having the fixed cathode tap connection. This selective connection is provided through the contact 31, which is connected with both the short wave tuning stator 27 and the grid end of the B band coil 12 through the lead 39. This connection is maintained by the movable switch conductor 22 engaging the contacts 23 and 31 continuously as it successively engages the contacts 21 for the short wave band coils.

By this arrangement, a compound Hartley circuit is provided for the short wave bands, with the cathode tapped near the center of the lowest frequency band spread oscillator coil, and the higher frequency oscillator coils are successively connected in shunt across this coil and with the oscillator grid circuit and tuning capacitor stator, without shifting the cathode tap and by merely making successive grid connections with the shorter wave band coils.

The switching connection thus effectively changes only the grid connection with the grid ends of the successive untapped coils, while all other connections in the oscillator circuit are maintained substantially fixed. The switching arrangement, therefore, for the band spread and short wave ranges is reduced to a single switching operation for the oscillator circuit with the successive high potential ends of the tuning coils.

As previously pointed out, the band changing switch 18 is shown schematically on the diagram

in a projected plane and, in order to permit a better understanding of the operation, the contacts are shown displaced with respect to their normal positions on opposite sides of the moving elements. For example, the contacts 67 through to 32 would normally occupy certain of the dotted positions indicated at 75, the contact 32, for example, being the same as the contact 61, and for this reason the two contacts are shown interconnected by a lead 76.

The tuning inductances for the narrow band, short wave tuning in the 49 to 19 meter bands are provided preferably with adjustable magnetic cores 71, whereby the initial tuning adjustment may be made, and this type of tuning is also provided for the A band coil 11, as indicated at 78. The A band coil is also provided with padding capacitors 79-79, and is connected with automatic frequency control leads indicated at 80, whereby suitable means may be provided for automatic frequency control on the A band if desired. The capacitor 81 is an additional trimmer capacitor provided in shunt with the main variable tuning capacitor for the A band only.

25 The oscillator is provided with a grid leak 82, and is adapted for automatic volume control from a circuit 83 connected to the grid through a series resistor 84.

The operation of the oscillator is such that it is selectively tunable through frequency ranges corresponding to the main broadcast band and the series of narrow band short wave tuning ranges, as well as other ranges, such as the B and C bands, with proper intermediate frequency separation, utilizing the Hartley circuit and an effective variable tuning capacitor arrangement comprising two sections, one of which is for the standard broadcast band and the other of which is for the short wave bands. The latter may 40 be the only variable tuning element in circuit in the receiver for the narrow band or band spread ranges in certain receiver designs.

In covering a large number of differing frequency bands, it may be necessary and desirable 45 to provide an additional cathode tap on the coil having the highest inductance in a particular group of coils. For the lowest frequency range and highest inductance coil in a particular group of coils, such as the band spread coils for the 49, 31, 25 and 19 meter bands, the cathode tap is made upon the coil 14. This connection may be provided in a case where the continuously tunable, medium and short wave bands B and C are eliminated for the sake of simplifying the 55 tuning system to a greater degree.

Also, it may happen that either one section or the other of the coil providing the cathode tap may resonate in one or more of the tuning ranges of coils which are to be switched in shunt therewith, in which case a cathode tap may be made 60 on an additional higher frequency coil providing the next largest inductance.

A switching arrangement for meeting a condition of operation where an additional tap is made 65 upon the highest inductance coil of a group in the short wave band is shown in Fig. 2, wherein a similar system to that shown in Fig. 1 is provided, with like parts bearing the same reference numerals as in Fig. 1.

70 Referring to Fig. 2, the oscillator tube 5 is arranged to be connected with the tuning band coils 11 to 11, inclusive, and with the variable tuning capacitor 19 through the switch 18, to provide tuning in the various bands in conjunction 75 with the tuning capacitor stators 26 and 27,

in the same manner as described in conjunction with Fig. 1. The right hand contacts on the switch, however, have been moved, together with the movable conductor element 22, into a slightly differing relation to the left hand fixed contacts and the movable conductor elements 47 and 51.

The connections of the right hand fixed contacts have also been slightly altered for the purpose of permitting an additional cathode tap on 10 the 49 meter band coil 14, as indicated at 90. As above mentioned, this has been found to be desirable when either section of the tapped coil normally used, such as the tap 12 for the B band, is found to resonate within the tuning band of 15 certain of the higher frequency coils which are to be switched in parallel therewith. In the present example, if the B band coil is found to resonate with its distributed capacity, within the C band or any of the other higher frequency bands, 20 the additional tap 90 is made upon the next lower inductance coil, which may be the 49 meter coil in the present example.

In doing this, the contact 55 of the switch is utilized to provide the tap connection through 25 a lead 91 with the tap 57 on the B band coil 12, and the contact 56, formerly utilized for the B band coil tap, is connected through a lead 92 with the tap 90 on the 49 meter band coil, so that the 49 meter band coil is connected into circuit and remains in circuit for the C band and the narrow band or band spread ranges for the 49 to 19 meter bands, as the cathode tapping coil.

With the contacts shifted as shown, whereby 35 the contact 66 is opposite the lowermost contact 21, the 49 meter high frequency secondary terminal is connected through a lead 93 with the contact 23, which is opposite the contact 44. The B band high frequency terminal is connected 40 through the B band series tuning capacitor 35 and a lead 94 with the contact 65, and the A band coil is connected through the series tuning capacitor 34 and a lead 95 with the contact 66. Otherwise the connections with the left hand 45 contacts of the switch are the same and for the same purpose as in the circuit shown in Fig. 1.

Since the contact 56 is utilized for connecting the tap 90 on the 49 meter band coil with the cathode lead 43 through the contacts 44 and 50 45 when the switch is moved to the C band position, but not for the B band position, the length of the movable conductor element 51 is such that it does not engage the contact 44 until the C 55 band position of the switch is reached.

The grid of the oscillator is coupled directly to the tuning capacitor stator 27 and to the grid capacitor 20, and is also connected to the fixed switch contact 70 which is arranged to engage the movable conductor element 22. The stator element 26 is also connected to the movable conductor element 22 through the contact 64, in series with a fixed capacitor 36 which is effective for the C band as well as the A and B bands.

In the A band position shown, it will be seen 65 that the A band coil 11 is connected through the contact 66 and the contact 24 of the movable conductor 70 22, to both sections of the capacitor 19 and to the grid of the oscillator. In the second position, the contact 65 for the B band is connected to the grid of the oscillator and to both sections of the capacitor 19. In the third position, the contact 64 and the contact 21 for the C band are bridged and the oscillator grid and tuning capacitor section 27 remain connected in 75

circuit as before. At the same time, the conductor 22 engages the contact 23 and places the 49 meter band coil 14 in parallel with the C band coil to provide the cathode tap for the C band tuning which is then completed through the movable conductor 51, then in engagement with the contacts 56 and 44.

The B band center tap is made in the second position of the switch when the contact 48 engages the contact 55. This connection is opened as the contact 48 moves beyond the contact 55, for the C band position.

In the 49 meter band position, the contact 24 of the switch conductor 22 engages a contact 97 which is connected with a trimmer capacitor 98 for the 49 meter band and, since the contact 64 is then out of circuit, only the smaller section of the stator, 27, is utilized for tuning in this band and the following band spread or narrow band tuning ranges. For each of the subsequent high frequency band positions, the coils 15, 16 and 17 are successively connected with the conductor 22 which then bridges the contacts 70, 23 and the contacts 30, 31 and 32 in succession to increase the load across the oscillator circuits as hereinbefore described, and thereby to provide stability of operation, through the addition of the capacitors 63, 68 and 69.

In this arrangement, each of the coils 13, 15, 30, 16 and 17 are successively connected in parallel with the cathode tapped coil 14 by switching a single grid connection to the successive coils, thereby greatly simplifying the switching required. In addition, it will be seen that provision has been made for additionally tapping a second coil to eliminate distributed capacity resonance of one tapped coil from falling within the tuning range of the remaining coils of the sequence, in adjusting the wave band response 40 toward the high frequency end of the tuning range of the oscillator.

In certain designs, depending upon the type of tube and the available voltages, it may become desirable to provide additional feed-back for the oscillator on the higher frequency range, in which case, as shown in the present example, the oscillator anode is coupled back to the highest frequency secondary coil through a coupling coil indicated at 99, and is then connected to ground 50 along with the screen grid through the capacitor 61 and the ground 60, as shown. In this manner, the feed-back is also applied to the grounded portion of the cathode tapped coil to provide the oscillator feed-back in each band.

55 As in the preceding embodiment, the oscillator is adapted to operate in conjunction with a multiple wave band superheterodyne receiver, in which case the switch is provided as one section of a gang and the tuning capacitor is likewise connected to the tuning capacitors of the other tuned circuits of the receiver, as indicated.

In the present example, as in Fig. 1, the oscillator potential is delivered to the mixer or converter tube through the output lead 25 connected 65 with the cathode lead 43, coupling in the present example being provided by a coupling capacitor 100 across a grid or output coupling resistor 101. This connection is made preferably to a suitable mixer grid in the converter tube (not shown).

70 In the present example also, the padding capacitors for the A band coil 11 are omitted for the reason that they may be placed in the automatic frequency control apparatus, connection 75 with which is indicated by the leads 80.

Since the operation of this embodiment is the same as the preceding embodiment, except for the feed-back on the highest frequency band and the provision of additional tapping of a second wave band inductance for the cathode circuit, 5 further description is believed to be unnecessary.

From the foregoing description, it will be seen that a stabilized Hartley oscillator circuit may be provided in accordance with the invention with a minimum number of switching connections to cover a relatively large number of wave bands, and that by means of separate coils for the short wave broadcast bands, full scale tuning may be obtained in each band, thereby providing band spread in the oscillator to at least as great 15 an extent as in the domestic or standard broadcast band, and that, in addition, other tunable bands may be provided whereby the oscillator is made to cover a relatively wide frequency spectrum. 20

A preferred application of the invention to a radio receiving system of the superheterodyne type contemplates the omission of the coils for the B and C bands, and the use of only the broadcast and the 49, 31, 25 and 19 meter bands, 25 whereby the switching may further be simplified by the omission of contacts and connections necessary for these additional B and C bands. In this manner the oscillator may provide signals for mixing in the main broadcast bands 30 for both foreign and domestic reception, with the wide range tuning of the short wave bands in widely spaced bands of relatively narrow kilocycle width, while the same tuning control may be used for all bands with the same scale width 35 of tuning indication.

The use of two differing tuning capacitor sections, with a common rotor and selective switching means for the sections, permits the oscillator to be tuned more effectively and to provide a 40 higher and more uniform voltage output through the use of proper design of and higher inductance in the tuning coils.

It will also be seen that by providing separate 45 tuning bands for the short wave broadcast frequency ranges, a coil design may be utilized such that a differing intermediate frequency may be produced for the short wave bands than for the broadcast band in any or all of the short wave tuning ranges. 50

By providing an oscillator having a plurality of tunable frequency ranges, one of which may cover a frequency range corresponding to the standard broadcast band of substantially 1,000 kilocycle width, and a plurality of relatively narrow band tuning ranges of substantially lesser kilocycle width, the band spread on the tuning dial of the receiver may, in the short wave bands, be made equal to or greater than that for the first named frequency band, and the oscillator 60 may be utilized as the tuning means for the receiving system in the short wave bands. 55

I claim as my invention:

1. A multiple frequency range oscillator for multiple wave band signal receiving systems and the like, comprising in combination, an oscillator tube having control grid, cathode and anode electrodes, tuning means for the oscillator including a variable tuning capacitor and a plurality of tuning inductances adapted to be tuned 70 thereby through a plurality of differing frequency ranges, each of said tuning inductances being connected at one end to the anode electrode, means for connecting said tuning capacitor and the oscillator grid jointly with the oppo- 75

- site end of each of said inductances selectively, means providing connections for maintaining one of said inductances in circuit with said tuning capacitor and grid for a plurality of said selective connections, and means providing a fixed cathode tap connection on said last named inductance only.
2. A multiple frequency range oscillator for multiple wave band signal receiving systems and the like, comprising in combination, an oscillator tube having control grid, cathode and anode electrodes, tuning means for the oscillator including a variable tuning capacitor and a plurality of tuning inductances adapted to be tuned thereby through a plurality of differing frequency ranges of substantially equal kilocycle width, each of said tuning inductances being connected at one end to the anode electrode, means for connecting said tuning capacitor and the oscillator grid jointly with the opposite end of each of said inductances selectively, means providing connections for maintaining one of said inductances in circuit with said tuning capacitor and grid for a plurality of said selective connections, means providing a fixed cathode tap connection on said last named inductance only, and selective switching means for controlling said grid and cathode connections jointly in predetermined relation to each other.
3. A multiple frequency range oscillator for multiple wave band receiving systems and the like, as defined by claim 1, further characterized by the fact that means are provided for tuning said oscillator through a frequency range having a kilocycle width greater than said first named frequency ranges and that said first named frequency ranges are of substantially equal kilocycle width.
4. In a tunable oscillator, the combination of an oscillator tube having an anode, a cathode and an input grid circuit, a variable tuning capacitor, means providing a plurality of wave band tuning inductances each having a feedback connection with the anode, one of said inductances having a higher inductance value with respect to others of said inductances for tuning in a lower frequency band, means for connecting said grid circuit and said variable tuning capacitor jointly in parallel with each of said inductances selectively, means for maintaining said parallel connection for said one inductance throughout a series of said selective connections for certain of said inductances, and means providing a connection for said cathode with said one inductance intermediate its terminal ends.
5. A multiple frequency range oscillator for multiple wave band signal receiving systems and the like, comprising in combination, an oscillator tube having a control grid, a cathode and an anode electrode, means providing an alternating current path to ground for said anode electrode, tuning means for said oscillator including a variable tuning capacitor, and a plurality of tuning inductances adapted to be tuned thereby through a plurality of differing frequency ranges, each of said tuning inductances being connected to ground at one end, selective switching means for connecting said tuning capacitor and the oscillator grid jointly with each of said inductances at the ungrounded end thereof, additional means independent of said last named means for maintaining the lowest frequency inductance in circuit connection with said tuning capacitor and grid, and means providing a fixed cathode tap connection for said tube on said last named inductance only.
6. In a multiple frequency range oscillator, the combination with an electric discharge device, of multiple frequency tuning means therefor comprising a variable tuning capacitor and a plurality of inductance coils adapted to be tuned thereby through a plurality of differing frequency ranges, each of said inductances being connected to ground, means providing a fixed anode circuit connection for said tube with one end of each coil and a fixed grid circuit connection for said tube with the opposite end of one coil for the lowermost frequency tuning range of a series of higher frequency tuning ranges, means providing a substantially fixed cathode circuit tap connection for said tube with said one coil, means for connecting a portion of the tuning capacitor selectively with each of said coils, and means providing selective grid circuit connections for said tube with each of a plurality of the remaining higher frequency coils in said series while said first named grid and cathode circuit connections are fixed.
7. In a multiple frequency range oscillator, the combination with an electric discharge device having a cathode, a control grid, and an anode electrode, of multiple frequency tuning means therefor comprising a variable tuning capacitor and a plurality of inductance coils adapted to be tuned thereby through a plurality of differing frequency ranges, each of said inductances having a grid terminal and an anode terminal, means providing a fixed alternating current path between the anode electrode and said anode terminals jointly, means providing a circuit connection between the grid terminal of a low frequency band inductance coil and the grid, means for maintaining said connection and selectively connecting said grid with each of the grid terminals of the remaining inductances successively, and means providing a fixed connection between an intermediate terminal on the first named inductance and the cathode, whereby a Hartley connection is provided in each of said tuning ranges successively by shifting the grid connection with the several inductance coils.
8. In a multiple frequency range oscillator, comprising an electric discharge oscillator tube having an anode circuit, a cathode circuit and a control grid circuit, the combination of tuning means therefor, including a plurality of tuning inductances at least one of which is tunable through a predetermined lower frequency range, and a plurality of which are tunable through spaced higher frequency ranges of lesser kilocycle width than the first named range, a variable tuning capacitor having a first section for tuning said first named inductance and a second section for tuning said plurality of inductances through said higher frequency ranges, means providing a common fixed anode circuit connection for said tube with one end of each of said inductances, means for connecting said grid circuit with the opposite end of one of said higher frequency inductances, means for maintaining said connection and selectively connecting said grid circuit with each of the remainder of said inductances, and means for maintaining a connection for said cathode circuit with an intermediate tap on said one inductance for each of said last named selective connections.
9. In a multiple frequency range oscillator, the combination with an electric discharge oscillator tube having anode, cathode and control

12. In a multiple frequency range oscillator,

JOHN D. REID.
